UNITED STATES PATENT OFFICE.

JACOB JENDRAL, OF BARNESBORO, PENNSYLVANIA.

RAIL-BRAKE.

1,311,072.

Specification of Letters Patent. Patented July 22, 1919.

Application filed February 28, 1919. Serial No. 279,841.

To all whom it may concern:

Be it known that I, JACOB JENDRAL, a citizen of the United States, residing at Barnesboro, in the county of Cambria and State of Pennsylvania, have invented new and useful Improvements in Rail-Brakes, of which the following is a specification.

My present invention pertains to rail brakes; and it consists in a peculiar and advantageous rail brake designed primarily for use in conjunction with mine cars, with a view to precluding running away of the cars, though it is adapted to serve efficiently in connection with rails and cars of various descriptions.

The invention in all of its details will be fully understood from the following description and claims, when the same are read in connection with the drawings, accompanying and forming part of this specification, in which:

Figure is a plan view showing my brake as properly arranged relative to a mine car and a track rail.

Fig. 2 is a transverse section taken in the plane indicated by the line 2—2 of Fig. 1, looking in the direction of the arrow.

Fig. 3 is an enlarged vertical section taken in the plane indicated by the line 3—3 of Fig. 1 and showing the eccentric mounting of the rail-engaging wheel.

Fig. 4 is a detail horizontal section, taken in the plane indicated by the line 4—4 of Fig. 2.

Similar numerals of reference designate corresponding parts in all of the views of the drawings.

At 1 is the rear portion of a mine car, and at 2 is the track rail in conjunction with which my novel brake is adapted to operate.

In furtherance of my invention I provide a beam 3. This beam 3 is provided at one end with a retractile tension device 4 for the connection of a chain or other cable 5 through which the beam is connected with the car body, preferably at the side thereof.

A portion of the beam 3 is in the form of an open frame 6, and in said frame is pivotally mounted a horizontal shoe 7, disposed in opposition to the outer side of the rail 2.

Pivotaly mounted in the frame 6 of the beam and disposed at the opposite side of the rail, with reference to the shoe 7, is a complementary shoe 8 that is adjustable as presently pointed out. Arranged in the

shoe 8 is a horizontal rail-engaging wheel 9, which is designed to extend through an elongated opening 10 in the inner side of the shoe.

Journaled in the shoe 8 and in the frame 6 is a vertical shaft 11, having a crank 12 at its upper end. The said shaft 11 is provided with an eccentric portion 13, which occupies a central aperture in the wheel 9. Carried in bearings 14 on shaft 11 is a vertical detent 15, having a crank 16 at its upper end, and normally pressed downwardly by a spring 16^a. The said detent 15 is designed to cooperate with apertures 17 in the upper wall of the frame 6 with a view to adjustably positioning the wheel 9 relative to the shoe 8 in which the same is arranged.

When my novel brake is to be used in conjunction with a mine car or similar car, I prefer to employ a platform 18, which is super-imposed upon and fixed to the upper wall of the frame 6, so as to afford a convenient stand for the operator, who will have for his duty to control the shaft 11 and the detent 15.

In the practical use of my novel brake mechanism, applied as shown and described, it will be manifest that when the shaft 11 is turned about its axis to disengage the detent 15 from the frame 6, the wheel 9 will operate after the manner of an eccentric cam, with the result that the two shoes 7 and 8 will securely grip the rail head and effectually brake the car. It will also be apparent that when deemed expedient the operator on the platform 18 may turn the shaft 11 and thereby thrust the wheel 9 against the rail head with a view to increasing the power of the braking action. When the detent 15 is disposed in the foremost aperture 17 the wheel 9 will be adjustably positioned relative to the shoe 8, so as to lessen the gripping action of the shoes against the rail head, and it will be noticed that as the detent is arranged in the apertures toward the rear end of the series the gripping action of the shoes will be still further diminished, until when the detent is in the rearmost aperture of the series the shoes 7 and 8 will slip along the rail head without taking hold thereof.

Inasmuch as my novel brake is designed to be employed in the nature of an anchor for mining cars, the connection of the cable 5 to the car may, when desired, be a detach-

able connection, so that the brake mechanism may be employed in connection with a number of cars in succession.

While designed primarily for use in connection with a mine car and one of the flat rails thereof, I would have it understood that the brake may be employed to advantage in connection with an elevator car and one of its guide rails or in connection with a car and rail of any other description.

I prefer to employ the specific construction and relative arrangement of parts as herein shown and described, but I do not desire to be understood as confining myself to the same, inasmuch as in the future practice of the invention various changes in the form and relative arrangement of the elements may be made without involving departure from the scope of my invention as defined in my appended claims.

Having described my invention, what I claim and desire to secure by Letters Patent, is:

1. A rail brake comprising a beam, a shoe carried by the beam and adapted to be op-

posed to one side of a rail, a shoe carried by the beam and adapted to be positioned at the opposite side of a rail, a shaft journaled in the beam and the last-named shoe and having an eccentric portion disposed in said shoe, and a wheel disposed in said shoe and receiving said eccentric portion of the shaft and adapted to engage the adjacent side of the rail.

2. A rail brake comprising a beam having an open frame portion provided in its upper wall with a series of apertures, a shoe pivoted in said frame portion and adapted to be opposed to one side of a rail, a shoe positioned in the frame portion and adapted to rest at the opposite side of a rail, and having a horizontal slot, a wheel disposed in said slot, a shaft journaled in the frame and the shoe and having an eccentric portion arranged in the wheel and also having a crank, and a detent carried by the shaft and adapted to seat in the apertures in the frame.

In testimony whereof I have affixed my signature.

JACOB JENDRAL.
